UNITED STATES PATENT OFFICE

THOMAS J. FOSTER, OF RIDGEWOOD, NEW JERSEY

SOUNDPROOF BUILDING CONSTRUCTION

Application filed February 2, 1929. Serial No. 337,091.

This invention relates to light weight, heat, damp and sound-proof floor or roof constructions comprising supporting beams carrying unitary floor or roof slab sections, and aims 5 to provide improved heat and sound insulating means for encasing the beams and supporting sectional slabs therefrom.

One of the objects of my invention is the provision of improved means supported from 10 the beam for encasing the beam to protect it in case of fire.

Another object is the provision of means assembled with the floor slabs, beam casings and beams to minimize transmission of sound 15 or vibrations from the floor to the beam.

A further object is the provision of elements including pre-formed parts which may be quickly and easily assembled in place and embedded or secured in hardening plastic 20 material to form a rigid heat and sound-proof floor or roof construction.

Further objects and advantages of my invention will be apparent from the following 25 description of preferred embodiments of my invention, illustrated in the accompanying drawings, wherein like reference numerals refer to the same parts throughout, and wherein:

Fig. 1 is a perspective view partly in section of one form of my invention, showing 30 the pre-formed parts assembled and ready for the application of the slab filling;

Fig. 2 is a transverse section through a beam of the form of construction in Fig. 1;

Fig. 3 is a transverse sectional view of the 35 same taken at line 3—3 of Fig. 2, showing the beam in side elevation;

Fig. 4 is an enlarged sectional view taken 40 at line 4—4 of Fig. 3, to show the manner of retaining the hanger members on the beam employed in this embodiment of the invention;

Fig. 5 is a perspective view of another embodiment of pre-formed beam encasement;

Fig. 6 is a similar view in which the 45 encasement has been lined with fire-resisting and sound-deadening material;

Fig. 7 is a perspective view of another form 50 of beam encasement, including spaced permanent forms, and arranged inverted and

with the bottom removed to show one manner of filling;

Fig. 8 is a perspective view of the embodiment of Fig. 7, filled, and arranged to show the manner of assembly with the beam, sound-deadening felt, and supporting hanger retaining means; and

Figs. 9, 10, 11, 12 and 13 are details of modified hanger and retainer means.

The illustrative embodiments of this invention shown in the drawings are particularly adapted for use in light floor or roof construction wherein the supporting beams or joists are spaced three or more feet apart, although the principles of the invention can obviously be applied to other floor or roof constructions.

In the following description the term "floor slab," is used to include roof-slabs, which are basically similar to floor-slabs, and may differ therefrom only in the top surface finishing coat which is not ordinarily a part of the slab-unit itself.

As shown in the drawings the joists or rafters may conveniently take the form of light weight I-beams 11, properly proportioned to carry the floor-load, and spaced to receive and support the pre-formed floor-slab elements and beam encasement and hanger means, as shown.

Floor slab unit

The floor slab unit is preferably formed as set forth in my copending applications Serial No. 221,780, filed September 24, 1927 85 patented September 29, 1931, Patent No. 1,825,346, and Serial No. 318,065, filed November 8, 1928 and comprises a unitary sheet 12 of stiff material adhesively or otherwise attached to sleepers 13, ordinarily composed of wood, which extend transversely of the space between the beams or joists 11, as clearly shown in Figs. 1, 2 and 3. The floor slab unit may conveniently have a width in the direction of sleepers 13 of about four feet, and a length transverse thereto of about eight to sixteen feet, corresponding to the spacing and span of the beams 11, though these dimensions may of course be varied at will and to 90 suit the conditions of use.

As set forth in my copending applications noted above, the sheets 12 are preferably coated on the upper side with a layer of waterproof material which may have sound-deadening qualities, or with layers of waterproofing and sound-deadening materials, generally indicated in Figs. 1, 2 and 3 by the reference character 14, and the adhesive used to fasten the sleepers 13 to the sheet 12 may have an additional sound-proofing effect. In addition the slab units may be provided with wire mesh reinforcing 15, and combined stiffening, handling and nailing screeds 16, attached transversely of the sleepers 13. The form of reinforcing 15 may vary with the material used as filler as hereinafter set forth, and the screeds 16 are of further use as guides by which to level the slab filler, and as spacing means to separate the forms when stacked. The screeds thus prevent injury to the bottom face of one form by the wires 15 of an adjacent lower form when stacked and during transportation. The lower face of sheet 12 may constitute the ceiling of the room below and may be left in natural finish, or plastered, painted or treated before or after assembly in the floor construction, as desired.

30 Beam encasement and floor slab supporting unit

In addition to the pre-formed floor slab units, I construct the beam-encasements and floor-slab-supports as units which may be swung into place, fastened to the beams and held against unfastening by retainers, thereby dispensing with forms and temporary supports, so that this assembly, and the placement of the floor-slab units, may be easily and rapidly accomplished.

These beam encasement and floor-slab-supporting units may take several forms, as shown in the drawings. The basic construction of all these forms is similar, and comprises a frame, made of wood or other suitable material; an outer wall fastened to the frame, which may be made of the same sheet material used for the floor slab, or other material for contrast; and hangers fastened to the frame by which to attach the unit to the beam or joist.

The frame in all the forms shown includes two parallel supporting runners 17 spaced so that they may receive the beam or joist between them, and held securely in position by U-shaped frame members 18. To this frame is secured the outer wall 19, of gypsum board or the like, and brackets 20 (see Figs. 1-6).

60 Figs. 1, 2, 3 and 5 show different views of a basic form of the encasement-floor-slab-supporting unit, as set forth above, for use without any additional heat or sound insulation, where such is not required. Fig. 6 shows the same basic form modified, however, in that the encasement unit is lined to

the depth of frame members 18 with hardened plastic material 31.

Figs. 7 and 8 show modifications of the encasement unit in which the hanger 20a, instead of bending under the runner 17 lies along the frame member 18 and is fastened thereto. In these figures the unit is also provided with a permanent inner wall 21, and the bottom portion 19a, as clearly shown in Fig. 7, is removed to allow filling in between walls 19 and 21 with any filling material 31a, plastic or granular, which has the sound-deadening and/or fire-proofing qualities desired.

The filled unit with wall 19a fastened back to the frame 18 in any suitable manner such as by nailing or use of an adhesive, is shown in Fig. 8, which also illustrates the mode of assembling the unit, sound deadening felt 23, and retainer 24 to the beam or joist 11.

Assembly of pre-formed units

Referring particularly to Figs. 5 and 8, it will be seen that hangers 22, which are pivotally attached to hanger brackets 20, swing down within the unit during transportation (see Fig. 5). When one of the units is to be assembled the first step taken is to bend down across the joist 11, a heavy sheet of sound-deadening material such as bituminized felt 23. Then the encasement unit, with the hangers 22 swung outwardly, is lifted up around the beam or joist 11 and the hangers 22 are swung inwardly above the felt 23 so that they are supported by the joist but insulated from direct contact therewith by the felt. A retainer, which may take the form of a spring clip 24 having lugs 25 engaging in recesses 26 of hangers 22, secures the hangers and prevents them from slipping from the beam or joist. (See Figs. 1, 2, 4 and 8.)

The encasement and slab-supporting units having thus been fastened in place, the floor slabs are swung into place and rested upon the runners 17. To prevent any shifting of the slabs, bridges or filler-pieces 27 are placed above the felt 23 and nailed or otherwise secured to the opposing ends of sleepers 13. These bridges may contact the top of the felt 23 to hold it securely down against the top surface of joist 11, as shown in Figs. 1 and 2. The top surfaces of these bridges 27 may lie in the same plane as the top surfaces of the screeds or nailing strips 16, for the same purposes.

The slab-units may be placed assembled only to the extent shown in Fig. 1, or they may be filled with plastic material before being swung into place. If pre-filled the only filling remaining to be done is that lying around the top of the joist 11 between the bridges 27. If not pre-filled these spaces and the slabs will preferably be filled at the same time. This will be done where it is desired to embed conduits and piping, or the like, in

the floor slabs. The filling used may be any sound-deadening and/or fire-proofing material, such as plastic gypsum, granular material, or the like. The depending edges 5 of the stiff, bituminized felt 23 serve to prevent any appreciable quantity of the filler from dropping down into the encasement unit and thus effect an economy of material. The use of short sections of felt immediately under the hangers 22 but not elsewhere is sufficient (and results in economy of felt) if the spaces above the felt are not to be filled, as in temporary structures, or if it is not desired to exclude the filler material from the interior 10 of the beam encasement.

Obviously details of the constructions above described can be modified, in various ways, for example, as shown in Figs. 9, 10, 11, 12 and 13, wherein modified hanger means 20 are shown. In Fig. 9, the retainer comprises wire or other suitable fastening means 24a, tying together the reversely turned ends of the modified hanger 22a; in Fig. 10, retention is effected by interlocking portions 24b 25 formed on the hangers 22b, themselves; and in Fig. 11 the entire hanger and retainer assembly is replaced by wires or other suitable means 24c, suitably attached to runners 17c, extending across the felt 23, and twisted 30 or otherwise fastened together, as shown.

In Figs. 12 and 13 a modified hanger means is shown, based somewhat on the form shown in Figs. 7 and 8. In this form of the invention runners 17d are cut away to form recesses 28 immediately above frame members 18. Hanger-brackets 20d are provided with upstanding ears 29, and lateral arms 30, and are fitted against frame member 18d below 40 runner 17a so that ears 29 extend upwardly within the recess 28 and lateral arms 30 bear against the under side of runner 17d. The hanger 22d is pivotally connected to upstanding ears 29 by a pin, as shown, and when, 45 after assembly, the brackets 20d are secured to frame member 18d, by suitable means, such as the illustrated bolts or screws, the hanger and hanger-brackets are inseparably held together.

50 This form of construction is extremely rigid and strong for the amount of material used, although it is not as cheaply and rapidly applied as the other forms shown. It is obvious, however, that any one of the forms 55 of my invention shown or described may be modified by substitution for elements thereof, corresponding elements from any other illustrative form, without departing from my invention.

60 I accordingly do not wish to be limited to the uses and embodiments shown and described, but claim as my invention all constructions falling within the scope of the following claims construed as broadly as is warranted by the prior art.

I claim:

1. In building construction, a plurality of spaced joists, sound deadening material resting on said joists, joist encasement and floor slab-supporting units extending under 70 said joists, means for supporting said units from said joists engaged with said sound deadening material to be sound insulated from said joists thereby, and floor slabs supported by said units.

2. In building construction, a plurality of joists, joist encasement and floor slab-supporting units hung from said joists but insulated therefrom by interposed sound-deadening material, floor slabs supported by said units, and bridge members extending across 80 said joists and tying together the slabs on the opposite sides thereof.

3. In building construction, a joist, a sound-deadening material resting on said joist, hangers resting on said sound-deadening material, retaining means securing said hangers in position thereon, runners supported by said hangers, floor-slabs supported by said runners, and a joist encasement supported from said runners and surrounding 85 said joist.

4. A pre-formed joist encasement and floor-slab-supporting unit for floor constructions comprising a frame made up of a pair 90 of parallel runners and frame members maintaining said runners in position and defining a space to receive the joist, an outer wall covering said frame, and movable hangers attached to said runners and adapted to engage 100 with the joist to support said unit.

5. In floor construction, a pre-formed joist encasement and floor-slab-supporting unit for floor constructions comprising a frame made up of a pair of parallel runners and frame members maintaining said runners in position and defining a space to receive said joist, an outer wall covering said frame, movable hangers attached to said runners and adapted to engage with the joist to support 105 said unit, and retaining means to hold said hangers in engagement with said joist.

6. A pre-formed joist encasement and floor-slab-supporting unit for floor constructions comprising a frame made up of a pair 110 of parallel runners and frame members maintaining said runners in position and defining a space to receive the joist, an outer wall covering said frame, and movable hangers attached to said frame and adapted to engage 120 with the joist to support said unit.

7. In floor construction, a pre-formed joist encasement and floor-slab-supporting unit for floor constructions comprising a frame made up of a pair of parallel runners and frame members maintaining said runners in position and defining a space to receive the joist, an outer wall covering said frame, movable hangers attached to said frame and adapted to engage with the joist to support 125 130

said unit, and retaining means to hold said hangers in engagement with said joist.

8. In floor construction, a joist, sound deadening material thereon, floor slab supporting means positioned laterally adjacent and in spaced relation to said joist, floor slabs supported laterally of said joist by said floor-slab supporting means, said floor slab supporting means comprising portions for support from said joist engaged only with the sound deadening materials thereon, whereby said floor slabs and supporting means are sustained by said joist but sound insulated therefrom.

15. In building construction, a plurality of joists, joist encasement and floor slab-supporting units hung from said joists, floor slabs supported by said units, and bridge members extending across said joists and tying together the slabs on the opposite sides thereof.

20. In building construction, a joist, hangers resting thereon, retaining means securing said hangers in position, a frame enclosing said joist and supported by said hangers, floor slabs supported by said frame, and a filling material supported by said frame and surrounding said joist.

25. A pre-formed joist encasement and floor-slab-supporting unit for floor constructions comprising a frame made up of frame members and a filling material and defining a space to receive the joist, an outer wall covering said frame, and movable hangers attached to said frame and adapted to engage with the joist to support said unit.

30. In building construction, a joist, a joist encasement and floor slab supporting unit extending under said joist, hangers attached to said unit and engaged with said joist to support the unit therefrom, means for retaining said hangers in engagement with said joist, and floor slabs supported by said unit.

35. A pre-formed joist encasement and floor slab supporting unit for floor constructions comprising a frame constituting a floor slab support and made up of frame members defining a space open at the top to receive the joist, an outer wall covering the sides and bottom of said frame, and hangers attached to said frame and adapted to engage with the joist to support said unit.

40. In testimony whereof, I have signed my name to this specification.

55. THOMAS J. FOSTER.
